Primary Examiner — Cynthia Ramirez*(74) Attorney, Agent, or Firm* — Quinn Law Group, PLLC.(57) **CLAIM**

The ornamental design for a combined annular flux collector and valve body, as shown and described.

DESCRIPTION

FIG. 1 is a top view a combined annular flux collector and valve body showing my new design;

FIG. 2 is a bottom view thereof;

FIG. 3 is a back view thereof;

FIG. 4 is a front view thereof;

FIG. 5 is a side view thereof;

FIG. 6 is an opposite side view thereof;

FIG. 7 is a perspective view thereof, with the flux collector shown in an exploded view;

FIG. 8 is a perspective view thereof; and,

FIG. 9 is a cross-sectional view thereof taken at the lines 9-9 in FIG. 8.

The broken lines showing the valve body extension is included for the purpose of illustrating environment and forms no part of the claimed design.
